A. C. WOOD.
MAGNETIC SPEEDOMETER.
APPLICATION FILED OCT. 16, 1920.

1,415,079.

Patented May 9, 1922.

UNITED STATES PATENT OFFICE.

ANDREW C. WOOD, OF CHICAGO, ILLINOIS, ASSIGNOR TO STEWART-WARNER SPEEDOMETER CORPORATION, OF CHICAGO, ILLINOIS, A CORPORATION OF VIRGINIA.

MAGNETIC SPEEDOMETER.

1,415,079.

Specification of Letters Patent. Patented May 9, 1922.

Application filed October 16, 1920. Serial No. 417,448.

To all whom it may concern:

Be it known that I, ANDREW C. WOOD, a citizen of the United States, and a resident of the city of Chicago, in the county of Cook and the State of Illinois, have invented certain new and useful Improvements in Magnetic Speedometers, of which the following is a specification, reference being had to the accompanying drawings, forming a part thereof.

The purpose of this invention is to provide an improved construction of magnetic speedometer, particularly with respect to the means for compensating for temperature changes and compactness of construction. It consists in the elements and features of construction shown and described, as indicated in the claims.

In the drawings:

Figure 1 is a section axial with respect to the rotor of a speedometer embodying this invention through the portion of the case containing the same.

Figure 2 is a top plan view of the structure shown in Figure 1.

Figure 3 is a section at the line, 3-3, on Figure 2.

A is the casing of the instrument in which the speedometer mechanism is contained, the same being made of either magnetic or non-magnetic material and having an interiorly projecting mount, A¹, axially bored for receiving spaced apart along the axis of the bore, ball bearings, 1, 1, for the shaft, 2, of a rotor for carrying the magnet, as hereinafter more particularly described. The shaft, 2, is reduced in diameter from one end to form a tapered journal at 2^a for one of the ball bearings, and at the extreme end to afford a cylindrical seat, 2^b, for the adjustable or wear-compensating cone journal member, 2^c. Intermediate the two ball bearings, this shaft carries rigidly, and preferably formed integrally with it, a gear member, 3, which in the structure shown is a worm gear for meshing with a worm, 4, on a drive shaft, 5, for which the mount, A¹, has an aperture, a¹, transverse to the axial aperture, a, and opening laterally into said axial aperture for the intermeshing of the worm and the gear. The rotor shaft, 2, is hollow from end to end for permitting the extension through it of the spindle, 6, of the non-magnetic drag member, 7, hereinafter

more particularly described. And the adjusting screw, 8, by which through the interposing spring washer, 8^a, the compensating cone member, 2^c, is adjusted on the reduced cylindrical part 2^b, of the shaft, 2, is axially apertured to permit the spindle, 6, to extend through it, and reach a step bearing, 10, which is mounted in a cover plate, 11, which encloses the enlargement or counterbore, 10^a, of the axial aperture, a, of the mount, said counterbore being necessary to admit the rear or bottom ball bearing, and accommodate the compensating cone and its adjustment. The shaft, 2, carries rigidly the magnet mount, 12, which is of non-magnetic material and has rigidly mounted upon it a split ring magnet, 13, and also by securement to the end of flat face of the mount, the field-deflecting member, 15, which is arcuate in form and extends from the point of its mounting by means of the securing screws, 16, in an arc corresponding approximately to the magnet path of rotation, and substantially parallel to the face of the magnet,—that is, in a plane at right angles to the axis,—to a point opposite the magnet gap slightly beyond which it extends. This field-deflecting member is constructed also for serving the purpose of a temperature-compensating device, and is for that purpose bimetallic, consisting of two laminæ of metals having different coefficients of expansion under temperature change, one being magnetic, the metal having the higher coefficient being on the side away from the magnet, so that upon rise of temperature, 90 the field deflector tends to become flexed concave toward the magnet so that its free end moves toward the magnet, thereby increasing its effect for deflecting the lines of force of the magnetic field, and increasing 95 the number of said lines which are cut by the drag member, 7. The drag member, 7, is a disk carried by means of a graduated cup, 7^x, whose outer wall has the graduations for speed indications exposed for reading 100 through the side opening, X, of the casing, and whose bottom is secured fast at the center to the spindle, 6, for oscillating in a plane parallel to the plane of rotation of the magnet between the side of the magnet and the 105 field deflector hereinafter mentioned. As a convenient means of securing the drag disk to the cup, 7^x, said disk is made cupped or

flanged as shown, and dimensioned for making a pressed or drive fit within the graduated flange of the cup, 7.

The field deflector, 15, is resilient and normally shaped so that it trends slightly away from the plane of the upper end of the mount, 12, to which it is secured at one end; and at the short distance from its point of securement, an adjusting screw, 18, is set through it into the mount, having its head engaging outside the member, 15, so that by screwing said screw inward more or less after the head comes into contact with the outer surfaces of said deflector, 15, said member is sprung toward the magnet pole at its free end. The original deflection of said member, 15, from a true plane is such as to cause its free end to stand off from the magnet somewhat more than the maximum distance by which it should be separated from the magnet in order to produce the necessary deflection of the field; and by setting the screw in more or less this distance may be varied to calibrate as is necessary in view of the unavoidable variation in the strength of different magnets.

25 is a hair spring preferably of non-magnetic material, as bronze, connected at one end to an arm, 26, mounted on the case, and on the other end to a spindle, 6, of the drag member, operating in the usual manner for resisting the drag of the rotating magnet upon said drag member. Said arm, 26, affords bearing for the upper end of the spindle, 6, and there is preferably provided a spring stop finger, 27, for checking the upper end of the spindle, causing its lower end to remain seated in the step bearing formed by a jewel, 29, mounted in the bearing member, 10, above mentioned, and secured by the check ring, 30, screwed into the upper end of said bearing. The material of all of the parts not specifically described as magnetic or non-magnetic may be any material suitable for the mechanical service required.

I claim:—

1. In a magnetic speedometer, in combination with a rotor, a magnet device mounted thereon for rotation in a plane containing all the magnet poles; a field-deflecting member carried by the rotor extending opposite the magnetic gap; a drag member pivoted for oscillation about the axis of the rotor, extending in the plane of its oscillation

proximate to the magnet and to the field-deflecting member; a carrier for the drag member which extends from the pivot spindle of the latter radially past the outer margin of the field-deflecting member and thence transversely of the plane of rotation of said member outside the path of rotation thereof to reach the drag member for securement of the latter thereto.

2. In a magnetic speedometer, in combination with a rotor, a magnet device mounted thereon for rotation in a plane containing all the magnet poles; a field-deflecting member carried by the rotor extending opposite the magnetic gap; a drag member pivoted for oscillation about the axis of the rotor, extending in the plane of its oscillation proximate to the magnet and to the field-deflecting member, said field-deflecting member being temperature-responsive for causing its movement toward and from the magnet under changes of temperature.

3. In the construction defined in claim 2, foregoing, the thermostatic field deflector being in the form of a quadrant arm mounted by one end on the rotor and having the other end free for movement toward and from the magnet poles.

4. In the construction defined in claim 2 foregoing, the thermostatic field deflecting member being arcuate in approximate conformity to the magnet path of rotation, secured at one extremity to the rotor and at the other end free to move under flexure and intermediately stopped as to movement for carrying the free end toward and from the magnet poles, and means for adjusting the intermediate stop.

5. In the construction defined in claim 2 foregoing, the thermostatic field deflector being a spring bar arcuate in form in approximate conformity to the magnet path of rotation, secured at one end of its arc form to the rotor, and at the other end free to move under flexure, and an intermediate stop within the range of its resilient reaction away from the magnet poles, and means for adjusting said intermediate stop to limit its resilient reaction away from the poles.

In testimony whereof, I have hereunto set my hand at Chicago, Illinois, this 30th day of September, 1920.

ANDREW C. WOOD.
